UNITED STATES PATENT OFFICE.

CHARLES H. HISER, OF SPRINGFIELD, OHIO, ASSIGNOR TO THE SPRINGFIELD METALLIC CASKET COMPANY, OF SPRINGFIELD, OHIO, A CORPORATION OF OHIO.

DESIGN FOR A PEDESTAL FOR BURIAL-CASKETS.

No. 39,678.

Specification for Design.

Patented Dec. 1, 1908.

Application filed August 3, 1908. Serial No. 446,821. Term of patent 7 years.

To all whom it may concern:-

Be it known that I, CHARLES H. HISER, a citizen of the United States, residing at Springfield, county of Clark, State of Ohio, have invented a new, original, and ornamental Design for a Pedestal for Burial-Caskets, of which the following is a specification, reference being had to the accompanying drawing, forming a part thereof.

The figure is a perspective view of a ped-

estal for burial caskets, showing my new design.

I claim:

The ornamental design for a pedestal for burial caskets, as shown.

CHARLES H. HISER.
